UNITED STATES PATENT OFFICE

CHARLES N. BRISCO, OF MORGANTOWN, WEST VIRGINIA, ASSIGNOR TO UNION STOPPER COMPANY, OF MORGANTOWN, WEST VIRGINIA, A CORPORATION.

STOPPER.

No. 814,352.

Specification of Letters Patent.

Patented March 6, 1906.

Application filed September 21, 1905. Serial No. 279,420.

To all whom it may concern:

Be it known that I, CHARLES N. BRISCO, a citizen of the United States, residing at Morgantown, in the county of Monongalia and 5 State of West Virginia, have invented a new and useful Improvement in Stoppers, of which the following is a specification.

This invention relates particularly to non-refillable bottles employing a normally restrained spring to close and maintain closed 10 a valve, the spring being released from restraint by liquid action in case an effort is made to refill the bottle.

The primary object of the invention is to 15 provide an improved construction whereby greater certainty of operation is secured, particular attention being paid to insuring the integrity of the spring-restraining body under conditions of ordinary use without rendering less certain the release of the spring 20 when an effort is made to refill the bottle.

The invention is illustrated in its preferred embodiment in the accompanying drawings, in which—

25 Figure 1 represents a sectional view of a bottle-neck equipped with the improved stopper, the stopper being in the closed position; Fig. 2, a similar view with the stopper raised ready for pouring; Fig. 3, a bottom plan view of the operating knob or handle; Fig. 4, a section taken as indicated at line 4 of Fig. 1; Fig. 5, a broken section taken as indicated at line 5 of Fig. 4; Fig. 6, a side elevational view of a valve-guard employed; 30 Fig. 7, a bottom plan view of the same, and Fig. 8 a broken section taken as indicated at line 8 of Fig. 4.

In the construction illustrated, A represents the neck of a bottle of ordinary construction, and B the improved stopper applied thereto.

The device B comprises a tubular plug or member *b*, having a hollow frusto-conical extension *b'*, cemented in the bottle-neck and 45 formed with a valve-seat *b''*; a gravity-acting disk valve *b'''*, resting on the seat *b''*; a combination guide and valve-guard *b⁴*, firmly secured within the member *b* in the manner hereinafter explained; a combination housing and valve-stem *b⁵*, working through the guide *b⁴*; an operating disk or knob *b⁶*, secured by a bolt *b⁷* to the member *b⁵*, and an inner housing *b⁸*, having a detachable top *b⁹* and containing a coil-spring *b¹⁰*, normally held in

restraint by a V-shaped spring *b¹¹*, between 55 the prongs of which is confined a mutable body *b¹²*, disintegrable under the action of liquid.

The member *b* affords a chamber for the operative parts of the stopper. The downwardly-tapering frusto-conical extension *b'* is equipped at its lower end with a cork-flange *c*, which fits snugly within the bottle-neck and forms a support for the cement *c'*, which joins the member to the bottle-neck. As 60 shown, there is an offset *c²* between the cylindrical and conical portions of the member *b*, whereat is provided an annular recess on the lower side, which seats upon the upper end of the bottle-neck, leaving a depending external flange *c³* fitting over the top of the bottle-neck. The cement is injected before the member is seated, after which the member is forced down to its proper position. Above 65 the valve-seat *b''* the interior surface of the 70 conical portion *b'* flares upwardly, as indicated at *c⁴*, and is equipped with ribs *c⁵*, having approximately parallel guide-surfaces which maintain the valve *b'''* centered when it 75 opens in the operation of pouring. 80

The valve *b'''* may comprise a lower disk of cork and an upper disk of metal cemented thereto. The combination guide and valve-guard *b⁴* comprises a sleeve equipped externally with a flange *c⁶* and beneath said flange 85 with arms *c⁷*, which center the sleeve and two of which are entered in bayonet-sockets *c⁸*, with which the member *b* is internally provided, being held within said sockets by keys *c⁹*. The sleeve portion of the member *b⁴* is 90 provided at its lower portion with an internal flange *c¹⁰*, upon which rests a cork sleeve or lining *c¹¹*, having cut therein vertical slots *c¹²*, which register in the open position of the stopper with lateral ports *c¹³* in the hollow 95 stem *b⁵*. The internal flange *c¹⁰* is provided with vertical slots *c¹⁴*, which receive when the valve-stem is raised lugs *c¹⁵*, with which the lower end of the valve-stem is equipped. These lugs *c¹⁵* work beneath cams *c¹⁶* at the 100 lower end of the sleeve portion of the member *b⁴*, operating when the knob *b⁶* is turned (after first being lowered) to force the stem hard against the valve.

The member *b⁶* comprises a disk which projects over the member *b* and an annular flange *d*, which depends within the member *b'* and telescopes loosely with the upper portion 105

of the member b^4 . The flange d is provided externally with vertical lugs d' , which fit freely within the upper portion of the member b and serve to prevent a wire from being inserted spirally in an effort to tamper with the valve. The upper end of the stem b^5 is equipped with lugs d^2 , which enter sockets d^3 on the lower surface of the member b^6 , and the bolt b^7 , the nut of which is within the stem, completes the connection. The lower end of the stem is externally flanged and the end surface is equipped with small lugs, which when the stem is rotated to unlock the valve turns the valve on its seat to loosen it.

The spring-casing b^8 slides into the tubular stem b^5 from below, and its top bears against the internal shoulder in the stem, as shown. The end of the stem is closed by a disk d^4 , of cork, paraffin, or the like, making a water-tight closure. The cap b^9 makes a close sliding fit with the casing b^8 , and beneath it is an absorbent disk d^5 , which protects the soluble tablet b^{12} from moisture under ordinary conditions. The cap is provided on its upper surface with lugs d^6 , through which pass admission-ports, as shown. In order for liquid to enter the casing to act upon the soluble body, it would be necessary for a quantity thereof to collect above the cap and immerse the lugs d^6 , and this could only occur in case an effort were made to refill the bottle.

The manner of assembling the parts of the stopper need not be recapitulated, as this is obvious. The stopper is supplied to bottlers for use in connection with ordinary bottles, the bottles being provided with means for cementing it in place in the bottle-neck. In the closed condition the lower end of the stem bears upon the valve, and the stem is locked in its depressed position by the lugs c^{15} , located beneath the cam-surface c^{16} . A quarter-rotation of the valve-stem, effected through the medium of the knob b^8 , brings the lugs c^{15} beneath the slots c^{14} , permitting the stem to be raised, thereby freeing the valve, so that in pouring the valve is free to assume the dotted position shown in Fig. 2. In this position an annular passage about the edges of the valve, the valve-guard, and the lower portion of the knob permits egress of the liquid. In the pouring operation the liquid is directed away from the ports c^{13} and none can enter said ports. If, however, an effort be made to refill the bottle, the valve will be seated and liquid forced through the ports c^{13} in sufficient quantity to immerse the perforate lugs d^6 , wetting the pad d^5 and weakening the normally hard tablet b^{12} , thereby releasing the spring b^{10} in a manner now understood in the art. The spring upon release forces the casing or valve-follower b^8 downwardly, thereby automatically locking the valve in its closed position. Under such conditions it is impossible to free the valve from the lock, and the safeguard against refilling is

permanent. It should be remarked that in the closed condition of the stopper (shown in Fig. 1) the ports c^{13} are closed by the tubular cork-valve c^{11} , so that no injury would result were the bottle to be immersed in water, as for rinsing purposes.

The parts b , b^4 , and b^6 usually are of glass, and the other parts may be of any suitable materials. The tubular stem b^5 may be of metal, as it is substantially protected from liquid contact when raised, as shown in Fig. 2.

Changes in materials and in minor details are contemplated. Hence no undue limitation should be understood from the foregoing detailed description.

What I regard as new, and desire to secure by Letters Patent, is—

1. In a bottle-stopper, the combination with a valve-seat and valve, of a member provided with a guide and valve, a tubular stem working through said guide and provided with a port guarded by said second-named valve, a spring carried with said stem, operative upon release to automatically lock said first-named valve, and a mutable body housed in said stem subject to liquid action and normally operative to restrain said spring.

2. In a bottle-stopper, the combination with a valve-seat and valve, of a combination valve-guard and guide equipped with a valve, a tubular stem working through said guide and closed by said second-named valve when the stem is depressed, a spring operative upon release to automatically lock said first-named valve, and a mutable liquid-affected body housed in said stem and normally restraining said spring.

3. In a bottle-stopper, the combination with a valve-seat and valve, of a valve-guard provided with a guide, a tubular stem working through said guide provided with a port and having an open lower end, a hollow valve-follower confined in the lower end of said stem and having a detachable top provided with a port, a spring confined within said follower, a body subject to liquid action located adjacent to said second-named port and normally restraining said spring, said spring operating upon release to force the follower against the valve.

4. In a bottle-stopper, the combination with a valve-seat and valve, of a tubular stem provided at its upper portion with a port, a sectional spring-casing confined within the lower end of the stem and provided at its upper end with a port, a spring and mutable restraining body therefor, confined in said casing, a guide for the stem equipped with a valve for the first-named port, and a knob connected with and serving in the manual operation of said stem.

5. In a stopper, the combination with a valve-seat and valve, of a valve-guard equipped with a guide and thereat with a valve, and provided also with a cam, a tubu-

lar stem working through said guide and equipped with a cam coating with said first-named cam, said cam being vertically slideable in one position with relation to the valve-guard and having a port at its upper portion, a sectionally-constructed spring-casing confined in the lower end of said stem and provided at its upper end with a port, a spring and mutable restraining body therefor confined in said casing, and a knob operative to raise and lower and rotate said stem at will.

6. In a bottle-stopper, the combination of a plug equipped at its lower portion with a valve-seat, a valve, a valve-guard non-removably secured in the tubular plug, a stem extending through said guard and equipped at its upper end with a knob, and a spring and mutable restraining body carried by the lower end of said stem, for the purpose set forth.

7. In a bottle-stopper, the combination of a tubular plug having a downwardly-flaring extension equipped with a valve-seat and provided with an external flange at its lower end adapted to contact with the inner surface of a bottle-neck, a valve-guard non-removably secured in said tubular plug, a valve above said valve-seat and a stem above said valve extending through said valve-guard and equipped at its upper end with a knob.

8. The combination with a bottle-neck of a tubular plug having a downwardly-flaring extension equipped at its lower end with an external flange, cement supported on said flange between said extension and inner surface of the bottle-neck, a valve-seat carried by said extension, a valve, a valve-guard non-removably secured in the tubular plug, a stem working through said valve-guard and a knob connected with the upper end of said stem.

9. In a bottle-stopper, the combination of a tubular plug having an extension adapted to fit in a bottle-neck, said extension being provided with a valve-seat, a gravity-valve, a valve-guard comprising a sleeve equipped with an external flange and with projecting arms non-removably secured in the tubular plug, a valve carried by said sleeve, a tubular stem provided at its upper portion with a port, a knob connected with said stem, a

spring-casing confined in the lower end of said stem, and a spring and soluble restraining body therefor confined in said spring-casing, for the purpose set forth. 55

10. In a bottle-stopper, the combination of a tubular plug having a frusto-conical extension adapted to fit in a bottle-neck, said extension equipped with a valve-seat and provided internally above the valve-seat with guides for the valve, a valve-guard secured in the tubular plug and provided with a guide, a tubular stem working through the valve-guard, a spring and mutable restraining body therefor housed in the lower end of said stem, 65 and an operating-knob connected with the upper end of the stem, for the purpose set forth.

11. In a bottle-stopper, the combination of a valve-guard comprising a sleeve equipped at its lower end with cam-surfaces and provided with internal vertical slots, and a stem working through said valve-guard equipped at its lower end with lateral lugs adapted to engage said cam-surfaces in one position of 75 the stem, and to slide within said slots in another position of the stem, for the purpose set forth.

12. In a bottle-stopper, the combination of a tubular plug provided internally with 80 bayonet-sockets, a valve-guard equipped with arms received by said bayonet-sockets, and means securing said arms within said sockets, for the purpose set forth.

13. In a bottle-stopper, the combination of a tubular plug comprising a cylindrical portion and a frusto-conical extension joined thereto by an offset recessed on its lower side to fit on the top of a bottle-neck, thereby affording a depending flange adapted to fit 90 over the top of the bottle-neck, a valve-seat carried by said extension, a flange at the lower portion of the extension adapted to fit within the bottle-neck, a non-removable valve-guard within the cylindrical portion of 95 the tubular plug, and a stem working through said valve-guard, for the purpose set forth.

CHARLES N. BRISCO.

In presence of—
